UNITED STATES PATENT OFFICE

144,034

DESIGN FOR AN ELECTRIC FAN

Robert David Budlong, Chicago, Ill., assignor to Clifford Strom, Chicago, Ill.

Application June 9, 1945, Serial No. 119,998

Term of patent 14 years

(Cl. D26—7)

To all whom it may concern:

Be it known that I, Robert David Budlong, a citizen of the United States and a resident of Chicago, in the county of Cook and State of Illinois, have invented a new, original, and ornamental Design for an Electric Fan, of which the following is a specification, reference being had to the accompanying drawings forming a part thereof, and in which:

Fig. 1 is a perspective view of an electric fan, showing my new design;

Fig. 2 is a side elevational view of the same;

Fig. 3 is a top plan view of the same.

Fig. 4 is a bottom plan view of the same; and

Fig. 5 is a perspective view similar to Fig. 2, partly in section.

The sides of the electric fan opposite to that shown in Figs. 1 and 2 are the same as that shown in Fig. 1.

I claim:

The ornamental design for an electric fan, as shown and described.

ROBERT DAVID BUDLONG.
